REGISTER DECIMAL MARKERS

William S. Gabelmann, Convent, N.J., assignor to Realty and Industrial Corporation, Convent, N.J., a corporation of New Jersey

Original application May 27, 1957, Ser. No. 661,971, now Patent No. 2,969,181, dated Jan. 24, 1961. Divided and this application Aug. 7, 1958, Ser. No. 753,832

11 Claims. (Cl. 235—61)

This invention relates to calculating machines, computing machines or the like.

An object of this invention is to provide an improvement in a computing machine of the type that has several registers in an ordinarily shiftable carriage and also has several banks of digital keys for entering certain factors into a computation, and including elements for selectively indicating the location of a reference point such as a decimal, or other delineations, between adjacent orders of such registers and banks of keys.

Another object of the invention is to provide means for minimizing the subjective influence of the operator over sequence when following the prescribed mode of decimalizing operation steps.

Still another object of this invention is to provide an improved, inexpensively manufacturable pointer and rail therefor, which pointer is easily adjustable to indicate the location of a reference point or decimal, of a registration in a register.

It is a further object of the invention to provide a decimal location pointer and a rail therefor, preferably a channel strip with numerals or like symbols placed on the visible internal face of its base to facilitate adjustment of the pointer, the elevated sides of the channel serving to prevent marring of the internal face as during shifting of the pointer.

Still another object of the invention is to provide a shiftable marker for setting the marker to locate the decimal of a quotient in a register of a computing machine, which machine in each of successive cycles of operations, selects the one of predetermined quotient digits that has resulting relation with the highest order of the dividend and of the two highest orders of the dividend remainder divided by the highest order digit 1 to 9 of the divisor.

The foregoing and other objects and advantages of the invention will be more readily understood upon reference to the following description. It will be apparent, however, that those skilled in the art will be enabled to apply the teachings of this disclosure to various modifications as intended to be covered by the scope of the appended claims. The description is directed to a preferred exemplary embodiment of the invention illustrated in the accompanying drawings forming a part hereof, in which:

FIGURE 1 is a top face view of a calculating machine according to the invention, the carriage being shown in fragment in its leftmost position.

FIGURE 2 is a fragmentary top face view similar to that of FIGURE 1, but showing the carriage shifted all the way to the right.

FIGURE 3 is a fragmentary perspective detail view showing one form of movable indexing marker element engaged with its supporting channel rail, apart from the machine.

FIGURE 4 is a fragmentary perspective detail view of another form of movable indexing marker element carried on its supporting guide channel, apart from the machine.

FIGURE 5 is a view showing in cross-section the indexing marker element of FIG. 4 and its guide channel.

FIGURE 6 is a fragmentary perspective detail view of a still another form of movable indexing marker asso-

2

ciated with its channel support, apart from the machine.

FIGURE 7 is a fragmentary sectional elevational view taken substantially on plane 7—7 of FIGURE 1, showing principally a keyboard decimal marker and the decimal pointers and rails for the several registers, with dials, and omitting other parts for clarity.

This application is a division-in-part and continuation-in-part of my copending patent application, Serial No. 194,273, filed November 6, 1950, for Partial Product Calculating Machine (Patent No. 2,969,177) and is a division of my copending patent application, Serial No. 661,971, filed May 27, 1957, for Keyboard Decimal Markers and the Like (Patent No. 2,969,181).

GENERAL DESCRIPTION

15 The machine in which the present invention is embodied is disclosed in detail in the aforementioned parent application, Serial No. 194,273, and the division and continuation-in-part application thereof, Serial No. 661,971, to which reference may be had for a complete disclosure not otherwise repeated herein. A brief summary of the machine and its operations, however, is presented herewith in order to facilitate understanding of the use of certain decimal markers and the methods devised for setting them.

20 The machine shown in FIG. 1 embodies partial product and predetermined quotient devices, a shiftable carriage 1 which carries counter and accumulator registers 2 and 3, several banks of keys 4 for setting up factors in various arithmetical calculations, and a bank of multiplier keys 5. This machine, commonly known as a "four-rules calculator," performs the arithmetical calculations of addition, subtraction, multiplication, and division automatically.

25 Multiplication is direct, as distinguished from repeated addition in that the machine multiplies in a manner closely analogous to the method used in mental computations. Representations of products for digits 0 to 9 times 1 to 9 are provided for selection in accordance with the separate digits of the multiplicand and each multiplier digit. The 30 partial products thus obtained are then integrated into the final product.

35 Addition and subtraction calculations are performed by automatically treating the factors thereof as multiplicands, and multiplying the factors by "1." The product thus obtained of a subtrahend is registered subtractively by the 40 dials of the respective register. Selective means is also provided for effecting subtractive registration of other products.

45 Heretofore division computations have been performed by repeated subtraction or logarithmic processes. In this 50 machine division is accomplished directly by structural elements in a manner analogous to the method corresponding to the well known mental procedure in "long division." The mechanism used for a calculation in division includes means for deriving trial quotient digits and also makes use of the multiplying mechanism. This 55 means that when a dividend has been set up in register 3 and a divisor has been set up in keys 4 of the keyboard, the machine upon actuation by depression of either

60 division key 6 or 7 automatically selects a trial quotient and causes the multiplying mechanism to obtain the product of the divisor times the trial digit. The product is then subtractively registered in dividend register 3.

65 Selection of a trial quotient value is made from representations of quotient values provided for dividend numbers ranging from 0 to 99 divided by divisor digits 1 to 9, both inclusive. The trial quotient first obtained may be an "over-estimation." In that case, the mechanism automatically reduces the trial quotient by "1" and makes one or more further attempts to obtain the true quotient. 70 When the true quotient, a single digit, is so obtained, it is registered in register 2. Failures to obtain the true quo-

tient are evidenced by an over-draft from the dividend, which is automatically cancelled out by adding back into register 3 the amount subtracted therefrom, that is, the product of the divisor times the trial quotient which proved to be too large. In the majority of instances the trial quotient proves to be the true quotient. The need for repeating more than once the attempt to obtain the true quotient integer is relatively infrequent. "Under-estimation," i.e., selection of a too small quotient integer, is not possible, due to the positive stop arrangements, as explained in the afore-mentioned parent application.

Results and factors of the various computations are indicated in ordinarily disposed dials of registers 2, 3 and 8 as follows: Register 2, carried by the carriage, can indicate the multiplier, quotient, or the number of items in addition or subtraction as the case may be and, alternatively, the complement of any of the foregoing. Register 3, also carried by the carriage, similarly can indicate the product, dividend, sum, difference, or such complements thereof as are desired. Stationary register 8 shows for easy reading a currently set up factor on the keys 4. Each register includes dials as at 9, 10 and 11, the numerals of which are visible through suitable apertures on the respective overlying cover plates.

Each multiplier key 5 for values 1-9 exercises a control over the computing mechanism for setting up significant partial products and simultaneously serves as an initiatory control for effecting operation of the computing mechanism. The cycle of operations so instituted also includes the function of automatically initiating operations for an ordinal shift of the carriage. Depression of the "0" value key 5 serves to initiate an ordinal shift of the carriage without first having to excite the computing mechanism.

Selectively operable keys 12, 13 and 14, near the right hand edge of FIG. 1, are provided for controlling the direction of shift of the carriage as for multiplication. With key 12 in depressed position, the automatic ordinal shift of the carriage will be leftward, but with key 14 in depressed position instead, the ordinal shift will be rightward, as indicated by the arrows on these keys. In each instance, the carriage will shift in the opposite direction for return to a preselected start position with the use of carriage return key 15. With the nonshift key 13 in depressed position, the automatically operated shift initiating means is disabled.

The tabulating mechanism is so constructed as to stop the carriage at an ordinal position by directly causing the carriage traversing mechanism to stop its operation. The tabulating mechanism is brought into operation each time the carriage shifts to either end position. Such operation of the mechanism will also occur at an intermediate ordinal position as with the use of key 15 provided that pre-selection of that position is made by depression of an appropriate one of tabulator keys 16, which are self-lockable and are releasable upon depression of a "tab clear" key 17 at either end.

Add key 18 and subtract key 19 are in effect "1" value multiplier keys, but the cycles of operations instituted thereby do not include the automatic initiation of a shift operation. Two divide keys 6 and 7 are provided, either of which serves to initiate a division computation cycle of operations, provided the machine is properly set up for such a computation.

The machine is prepared for a division computation as follows: The carriage is shifted to its rightmost position, as illustrated in FIG. 2, preferably by the depression of extreme shift key 20, FIG. 1. The dividend is then set up in the multiplicand selecting mechanism by keys 4, preferably with the highest order of the dividend in the leftmost bank of keys 4. With the use of add key 18, the dividend is registered, that is to say, entered, in register 3 with the highest order appearing in the 19th order dial 9, FIG. 2, the lower of the two highest order inboard dials. (An inboard dial is one which is in operative relation

with the entry and carry mechanisms of the main body of the machine.) At this rightmost position of the carriage, the 19th dial is then in alignment with the leftmost keybank to receive a registration therefrom. Non-entry key 21 (FIG. 1) is depressed simultaneously with the add key 18 whereby the item "1" is prevented from appearing in register 2. The divisor is then set up in the multiplicand selecting mechanism by keys 4 with the highest order real digit, that is, a digit other than "0," in the leftmost bank. In addition to making a selection of relative partial products, the depressed key in the leftmost bank also effects selection of quotient representations in the dividing mechanism in accordance with the value of that key.

Depression of a divide key is prevented by a system of locks which are rendered ineffective only when both the carriage is in its rightmost position and a real digit key 4 is depressed in the leftmost bank. Operation of either key 6 or 7 excites a mechanism which conditions the machine (without upsetting current operational setups that may be incongruous with requirements for division) for subtractive entry of products, and for sequential operations of the division, multiplying and traversing mechanism, the latter to shift the carriage leftward. The conditioning mechanism also initiates operation of the dividing mechanism for the division process. With the use of key 7, the conditioning mechanism also renders the tabulating mechanism effective to cause termination of the division process upon registration of a predetermined number of quotient digits. First, however, the tabulating mechanism must be set by depression of that tabulator key 16 which corresponds with the number of digits desired. With the use of key 6, whether or not a tabulator key selection is made, or with the use of key 7 when a selection is not made, the tabulating mechanism will cause termination of the process only when the ordinal capacity of the machine is reached.

In algebraic division processes, the problem is "solved" whenever the dividend is eliminated, that is, reduced to "0". Sensing means, one for each dial 9, are all movable together and movement is obstructed when a dial 9 is displaced from "0" position, indicating a remainder. Accordingly, turning of all the dividend dials 9 to "0" position enables the sensing means to move, whereupon the sensing means effects termination of the division process automatically, there being no remainder and no reason for continuing the operations. Both the eliminated dividend sensing means and the tabulating mechanism operate a mechanism which terminates the division process by preventing the sequential re-initiation of the dividing mechanism after the final true quotient digit is registered in register 2.

The preferred method of carrying out a cycle of operations in a division process in this machine after the problem is setup is as follows: The value of the dividend digits in the two highest inboard orders of dials 9 of register 3, the 20th and 19th dials (FIG. 2) in the initial cycle, is sensed. (The value in the 20th dial being 0 and in the 19th the value being that of the highest order numeral of the dividend.) In accordance with the sensed dividend value, the significant quotient value representation of the divisor selected representations is set up inside the machine. Then the set up representation is sensed and concurrently the multiplier controls in the computing mechanism are adjusted for that trial quotient value. Next, a cycle of operations of the computing mechanism is automatically instituted, whereby the product of the divisor factor (the multiplicand) by the trial quotient digit (the multiplier) is subtracted from the dividend in register 3 and the trial quotient is registered in the first inboard order dial 10, of register 2, FIG. 1, the 10th or leftmost dial in the initial phase of the division process, at which time that dial is standing in alignment with the numeral "0" on the decimal marker channel 22. When subtraction of the product does not result in an over-draft, as would be indicated on register 3, a cycle of op-

erations is instituted automatically for shifting the carriage leftward one step. In the final phase of the shift cycle, operation of the dividing mechanism is instituted again, this time automatically, except, however, when the carriage has been shifted to its leftmost position, or to a preselected ordinal position, or whenever the dividend has been eliminated, showing that a solution has been reached. In the event an over-draft occurs, the over-drafting amount and the too large quotient digit entries are withdrawn from the respective registers 3 and 2. At the same time the dividing mechanism automatically reduces the value of the too large quotient digit by "1" and adjusts the multiplier controls accordingly. The multiplying mechanism is then automatically caused to obtain the product of the divisor factor times the reduced trial quotient value and to reduce the dividend by that product. If the value of a selected trial quotient or of a reduced trial quotient is "0," a shift cycle of operations for shifting the carriage one step leftward is automatically instituted instead of the normal subsequent multiplying process.

Selectively settable decimal marker members 23 (FIG. 1), 24 and 25 are provided for indicating decimals of factors set up by keys 4 and of registrations in registers 2 and 3 respectively.

DECIMAL MARKERS

Markers 23 in one form are elongated prismatic bars, the degree of elongation being made sufficient to suit the constructional needs and arrangements. Each bar is formed with more than two faces about its longitudinal axis, this being the axis about which it is mounted for turning. A bar 23 is disposed intermediate each adjacent banks of keys 4, there being nine such bars shown by way of example. These bar markers are rotatably mounted at their forward or proximal ends on upturned flange 26 (FIG. 7) of keyboard frame plate 27, and at their rearward ends on keyboard register cover plate 28 which is supported by plate 27. According to one preferred form, markers 23 are triangular in cross section, each normally having only one of its three faces visible to the operator, the face then being in a plane parallel with the plane of plate 27 which serves as the background for the keyboard, as viewed in FIG. 1.

Slightly rearwardly of flange 26 (FIG. 7) a turning means 29 is secured to each bar 23 for movement therewith. Each turning means protrudes upwardly through suitably located frame openings 30 on the over-hanging portion 31 of cover plate 32, which is in front of keys 4. This location is not only convenient for the operator but also avoids interference with or accidental depression of keys 4 while manipulating a turning means for rotating a selected bar marker so as to bring any one of its three faces into direct line of vision of the operator.

In one preferred form, the surface of one face of each bar 23 matches the visible surface of the background plate 27 so as to blend or merge therewith and thus be indistinguishable therefrom when brought into viewing position, thereby avoiding the representation of a decimal or of any other delineation. Each of the other two faces of the bars may be surfaced mutually similarly but differently from that of the background surface, or the two faces may be surfaced differently from each other and from the background plate or wall. Then when one of the differently surfaced faces of a bar is turned into viewing position it contrasts with the background, distinctly delineating the adjacent banks of keys, whereby to represent a decimal, a point, line or location of demarcation.

Referring to FIG. 1, selectively settable decimal markers or indexing members 24, 25, 40 and 41 are mounted respectively on channel rails 42, 43, 22 and 44. Channel rails 22 and 44 are secured respectively to cover plates 32 and 28 of the machine and rails 42 and 43 are secured to cover 45 of carriage 1 for movement therewith. Each member or rail is formed of flanges 46, as may be

best seen in FIG. 6, projecting divergently outwardly from web 47, and the decimal markers may be suitably shaped with depending spring fingers 48 to yieldably grip the inclined flanges 46, as shown, for sliding therealong. The markers are spaced from the channel web and are formed with indexing fingers 49 (FIG. 3) of a length sufficient to extend as between adjacent orders of the related register for decimalization of a registration therein, and these fingers may be marked with a suitable colored spot. A suitable knob 50 is secured to each marker for sliding or setting the marker from one decimalizing position to another. The ends of each of the rails are bent upwardly to form stops 51 (FIGS. 6, 7) for blocking endwise disengagement of the respective marker from the channel rail.

Referring to FIG. 1, the visible face of web 47 of each of the rails 22, 42 and 43 is marked as with numerals, preferably reading from right to left, to coincide with the register orders so as to facilitate positioning of the markers for decimalizing. These numerals may be marked on the visible face of web 47 in any well known manner, as by painting. The flanges 46 of the channels serve to prevent obliteration of such markings. It will be noted that rail 44 is preferably not provided with serialized indicia or markings, as are the other rails, and that decimal marker 41 thereon has two oppositely oriented indexing fingers 49a and 49b instead of one as do the other markers. The proximal finger 49a extends towards the keyboard so as to align selectively with key bank decimal markers 23, and the opposite finger 49b extends towards register 3 for indicating a decimal between adjacent orders of the dials therein.

Some of the rails are shown with more than one marker to facilitate use of the one closest to the location at which the operation is being carried on. A series of lines 52 are marked on machine cover 28 extending from dials 11 of register 8 toward the registers on the carriage. Coinciding lines 52 are continued on carriage cover 45 to dials 9 of register 3, dials 10 of register 2 toward the numerals marked on channel 22. These lines are provided for facilitating decimalizing. Methods for decimalizing operations for division and multiplication computations are explained hereinafter.

FIGURE 3 shows another form of slidable marker in which the top web extending across the channel rail has a depending skirt 48a with spring pressure fingers 53 extending therefrom to resiliency grip the underlying side flange of the rail. It is only necessary to have the pressure fingers 53 on one of the skirts 48a, inasmuch as that one pair of fingers acting against one outer face of the channel rail will draw the other two skirts 48a against the opposite outer face.

FIGURES 4 and 5 illustrate a further form of slidable marker in which there is a marker body with tapered lower portion 54 conforming to and extending inbetween the inner angle space of the channel, leaving clearance therebelow to avoid touching any numerals, or other indicia carried on the visible web face 47a. A spring clip 56 may be snapped into a shallow transverse groove 55 on the marker body, so that its spring fingers extend over and grip the outside flange surfaces of the rail, allowing controlled slidable positioning therealong. For increased wedging effect the two shoulders 57 riding on the upper edge of the rail flanges may, if desired, be omitted. The spring clip 56 may serve as a convenient lining pointer having a function somewhat similar to the pointer 49 of FIG. 3, and may be variously or brightly colored or surfaced to enhance its pointing effect, and may project partly above the marker body so that depression thereof spreads its fingers, releasing their gripping action for easy sliding.

DECIMALS IN DIVISION

The rules for the procedural sequence or steps for setting indexing means 24 (FIG. 1) for decimalizing quotients registered in register 2 will now be given. First,

however, it will be recalled that the machine can be cycled for the performance of a division calculation only when the carriage 1 is in its rightmost position, as shown in FIG. 2, at which time the 19th order dial 9 in register 3 is in direct alignment with the leftmost bank of keys 4, and when a divisor digit other than 0 is set up on those keys. Accordingly, the following rules of procedure apply:

(1) The given decimal in the divisor is moved mentally, and noted, so that it precedes the leftmost real digit.

(2) The given decimal in the dividend is moved mentally, and noted, identically as in the divisor, in direction and the number of orders.

(3) That keyboard decimal marker 23 (FIG. 1) is turned to decimalize which will set off as many key banks leftward therefrom as there are orders to the left of the moved dividend decimal.

(4) A decimal marker 24 is shifted so that one more order of dials 10 is set off to the left therefrom than the number of key banks to the left of the above turned marker 23.

(5) The dividend is then setup on the keyboard about the above turned marker 23 with the moved decimal thereof coinciding with the turned marker 23, and is entered into the machine as previously explained.

(6) The divisor is then setup on the keyboard with the highest order real digit thereof on the leftmost key bank.

(7) Then division cycling is initiated, preferably by key 6 whereupon the quotient is registered in register 2, correctly decimalized by the marker 24 preset as above explained.

The following three problems exemplify the application of the above rules.

Table No. 1

Problem as given	Rule	Moved decimals	Marker 23, rule 3	Quo. decimal, rule 4
(a) $\frac{92.}{275}$	2	.92.	2	(2 - 1) 334.5454545
(b) $\frac{92.}{275}$	1	.275		
(b) $\frac{92.}{275}$	2	.092	0	(0 - 1) 0.334545454
(c) $\frac{92.}{275}$	1	.275		
(c) $\frac{92.}{0275}$	2	.920	3	(3 - 1) 3345.454545

In the above Table No. 1, problem (b), the "0" under the "Marker 23" column indicates that in such instances no key banks are set off leftward of a marker 23. In fact, no marker 23 is turned for decimalizing, in this case, since the first real digit of the divisor must be set in the leftmost key bank and, in one preferred form, as is illustrated, no decimal marker 23 is provided left adjacent thereto. In another form, not illustrated, a marker 23 may also be mounted on the keyboard respectively left adjacent, and another marker 23 may be mounted right adjacent the leftmost and rightmost bank of factor keys.

When several quotients are to be accumulated, it is preferred that the 9th order dial 10 in register 2 be the highest order dial that may register a derived quotient digit so that the 10th order dial stands as an overflow order, only to register carries from the 9th order dial. In order to effect this, the dividend is so entered into the computation that at least the first derived quotient digit will be 0. Accordingly, the following rules apply:

(1a) The decimal in the divisor of each problem is moved mentally and noted as stated hereinabove for rule 1.

(2a) The decimal in the dividend of each problem is then moved mentally and noted as stated hereinabove for rule 2.

(3a) Then that marker bar 23 is turned to decimalize which sets off one more keybank to the left therefrom than the number of orders to the left of the moved deci-

mal in the dividend having the highest number of such orders.

(4a) A decimal marker 24 is then shifted so that one more order of dials 10 is set off to the left therefrom than the number of keybanks to the left of the marker 23 turned according to rule 3a.

(5a) The dividends are then set up on the keyboard about the turned marker 23 with the moved decimal of each coinciding therewith, and are entered into the machine as previously explained.

(6a) Each divisor is then set up on the keyboard with the highest order real digit thereof on the leftmost keybank 4.

(7a) After entering each dividend and setting up its respective divisor, division cycling is initiated preferably by key 6 whereupon each quotient is registered and totaled in register 2, correctly decimalized by the marker 24 which has been preset according to rule 4a.

Decimalizing the totaled quotients of three division problems A, B, and C, in accordance with the above rules is accomplished as follows:

Table No. 2

25	Given problem	Decimals moved	Quotients	
			Each	Totaled (on dials)
30	A $\frac{985.4}{.673}$	.985.4 .673	(001464.1901)	001464.1901
	B $\frac{985.4}{.673}$	.9854 .673	(000001.4641)	001465.6542
35	C $\frac{98.54}{.00673}$	.9854 .673	(014641.9019)	016107.5561

There are 4 orders of digits to the left of the moved decimal in problem C, the largest number of such orders of all the dividends. Accordingly, that decimal marker bar 23 is turned which sets off 5 key banks 4 leftward of the marker, and register 2 decimal marker 24 is shifted so that 6 orders of dials 10 are set off leftward therefrom. The dividends are entered about the turned marker 23 and the divisors are set up with the highest order real digit of each in the leftmost keybank. The quotient of each problem A, B, and C is listed in Table 2 in the column under the heading "Each." In the column under "Totaled" are the results as they would appear in register 2; the first result being the quotient of problem A, the second result being the sum of the quotients of problems A and B, and the third result being the sum of the quotients of the three problems.

In this embodiment limitation of a quotient to a desired number of digits may be accomplished in two ways. The preferred one of these methods is by presetting a selected tabulator key 16 and initiating division cycling by key 7. Selection of the tabulator key is simple. That key 16 is depressed which bears the numeral corresponding to the number of the dial 10 in register 2 in which the lowest order quotient digit is to be registered. If, for example the accumulated quotients C in Table 2 were to be limited to two orders right of the decimal, the last "wanted" digit appears in the dial of register 2 under the numeral 3 on channel 42. Accordingly, the tabulator key 16 bearing that numeral is depressed. Then upon cycling of the machine by key 7 for each of the problems A, B, and C in Table 2, each division process will terminate when the true quotient digit is derived and registered in dial 10 under the numeral 3. Thus the operator can determine to how many significant digits or decimal places the computation should be carried out, the machine stopping automatically upon reaching the predetermined place.

Another method for limiting a quotient is as follows: Marker 24 is located to set off as many orders of dials

10 to the right of the marker as the number of digits desired to the right of the decimal. Then that keyboard marker 23 is turned which sets off one more order of keybanks to the right therefrom than the number of orders of dials to the right of marker 24. The dividend and divisor are treated as set forth in rules 1, 2, 5, and 6, and key 6 is used for cycling of the machine.

DECIMALS IN MULTIPLICATION

Setting of a decimal marker 25 (FIG. 1) to mark off 10 decimally a product in register 3 is made in accordance with the well known principle of marking off a product so that the orders to the right of the decimal therein corresponds to the sum of the orders to the right of the decimal in the multiplier and in the multiplicand. The 15 ordinal, step-by-step shifting of the carriage during multiplication, as previously explained, may be made selectively either leftwardly or rightwardly; correspondingly, the multiplier must be entered into the machine by means of keys 5, as when reading the multiplier from left to right or from right to left. Multiplication may be initiated with the carriage in any one of its ordinal positions. Nevertheless, when products of a plurality of computations are to be accumulated, it is preferred to place the carriage in the same starting position for each computation. This may be accomplished by presetting that tabulator key 16 which bears the same numeral as the numeral on channel 42 above the dial 10 in alignment with the 0 mark 58 on the right of channel 22 when the carriage stands in its selected start position. Such a dial 10 will be referred to as the "start dial."

(1) In order to indicate the decimal in a multiplier in dials 10,

(a) With the machine in start position and conditioned for leftward ordinal shift of the carriage, a marker 24 is moved so as to set off as many dials 10 leftward therefrom (the first of such dials being the start dial) as there are orders to the left of the decimal in the multiplier, but

(b) With the machine in start position and conditioned for rightward ordinal shift, a marker 24 is moved so as to set off as many dials rightward therefrom (the first of such dials being the start dial) as there are orders to the right of the decimal in the multiplier.

(2) The multiplicand is set-up on keys 4 and that marker bar 23 is turned to viewing position which coincides with the decimal in the multiplicand.

(3) A marker 25 is then moved to set-off as many dials 9 to the right of the marker as the sum of the number of dials 10 to the right of marker 24 and of the number of keybanks to the right of the turned marker 23.

Another method for setting a marker 25, after setting markers 24 and 23 as set forth in rules 1 and 2, is to shift the carriage so that the first dial 10 left of marker 24 is in alignment with 0 mark 58, and then to move a marker 25 so as to align with the turned marker 23. The carriage is then returned to start position. This method eliminates the mental totaling called for in rule 3.

When two or more products are to be accumulated, marker 24 is set as in rule 1a in accordance with the multiplier having the largest number of orders to the left of the decimal, or as in 1b in accordance with the multiplier having the largest number of orders to the right of the decimal, depending on whether the multipliers are being entered as reading from left to right or right to left. The multiplicands are set up about a marker bar 23 turned to viewing position, and a decimal marker 25 for the accumulated products is preset as instructed in rule 3.

When working from left to right and multipliers having lesser number of orders to the left of the decimal than in the multiplier having the largest number of such orders are entered, zeros are entered before the leftmost digit of the lesser ordered multipliers to fill them out or to spread them to have the same number of orders as in the multiplier having the largest number of such orders. The purpose of this is to have the products of each prob-

lem registered in register 3 consistently about the preset decimal marker 25. The same principle applies conversely when working multipliers from right to left, in that the zeros are then filled in on the right end of the multipliers having lesser orders to the right of the decimal to make them equal in such orders to the largest of such ordered multipliers. In the table below are examples, the products of which are to be totaled and the multipliers of which illustrate the 0-spread principle.

Multiplicands	Multipliers	Spreads	
		Left shift and working L-R	Right shift and working R-L
475.83	175.346	175.346	653.571
97.989	8.74	008.74	047.8
9.01	.75	000.75	057.
(Marker 23)		(Marker 24)	(Marker 24)

Another set of markers 40 and 41 is provided on channels 22 and 44 for marking off the multiplier in dials 10 and the product in dials 9 respectively. These markers are stationary, i.e., they do not move with the carriage, and their setting is as follows:

When working from right to left, a marker 40 is positioned to set off as many orders of dials 10, up to and including the start dial as there are orders to the right of the decimal in the multiplier. Then marker 41 is shifted leftward from the turned marker 23 as many orders of key banks as the value of the numeral on channel 22 to the right of set marker 40. After completion of the computation the carriage is returned to its start position whereupon the markers 40, 41 mark off the respective registrations decimally correct.

When working from left to right, a marker 40 is positioned to the left of that numeral on channel 22, which numeral has the same value as the number of orders to the right of the decimal in the multiplier. Then marker 41 is shifted leftward from the turned marker 23 as many orders of key banks as the value of the numeral to the right of the set marker 40 on channel 22. Upon completion of the computation, markers 40 and 41 mark off the respective registrations decimally correct.

Accumulated products may also be decimalized by marker 41. Marker 40 is set as explained above in accordance with the multiplier of the group having the largest number of orders to the right of the decimal. When the multipliers are entered right to left, the orders to the right of the decimal are filled in or spread to equal the number of orders in the multiplier having the largest number of such orders. When the multipliers are entered left to right, the orders to the left of the decimal are spread to equal the number of orders in the multiplier having the largest number of such orders, and in the last computation the multiplier orders to the right of the decimal are spread, if necessary, to equal the number of orders in the multiplier having the largest number of such orders.

What I claim is:

1. A decimal point indicating device for the registers of a calculating machine comprising: a channel means of uniform thickness material and formed of a pair of substantially outwardly divergent continuously plane longitudinal flanges projecting directly from base web means therebetween, said base web means being securable to said machine and each said flange having an inner and an outer plane face and a longitudinal edge parallel to the same on the other flange, the edges of said flanges being spread a greater extent than the flanges at said base web means, and movable pointer indexing means constructed and arranged to ride on said edges and to yieldably grip only the outer faces of said flanges for slidably guided positioning therealong and for indexing appropriate decimal

numerical registrations in said register means, whereby said spread edges provide substantial support for said pointer indexing means with minimal frictional contact area between said edges and said pointer indexing means, while the area contact of said web means with said machine is minimized and wherein said pointer indexing means straddles said flanges and is formed with depending resilient fingers inclined inwardly against said outer faces of said flanges for yieldably frictionally gripping said outer faces of said flanges intermediate said edges and the intersection of said flange with said web means and spaced from said web means for holding said indexing means at any decimalizing position therealong.

2. A decimal point indicating device for the registers of a calculating machine comprising: a channel means of uniform thickness material and formed of a pair of substantially outwardly divergent continuously plane longitudinal flanges projecting directly from base web means therebetween, said base web means being securable to said machine and each said flange having an inner and an outer plane face and a longitudinal edge parallel to the same on the other flange, the edges of said flanges being spread a greater extent than the flanges at said base web means, and movable pointer indexing means constructed and arranged to ride on said edges and to yieldably grip only the outer faces of said flanges for slidably guided positioning therealong and for indexing appropriate decimal numerical registrations in said register means, whereby said spread edges provide substantial support for said pointer indexing means with minimal frictional contact area between said edges and said pointer indexing means, while the area contact of said web means with said machine is minimized and wherein said pointer indexing means straddles the edges of said flanges and is constructed and arranged with a first skirt and at least one second skirt depending from opposite sides of said indexing means, said first skirt being resilient for yieldably gripping on the outer face of one of said flanges and for drawing said second skirt against the outer face of the other of said flanges, both said skirts conforming with the spread angulation of the outer faces of said flanges and, under the influence of said resilient first skirt and the cooperation of both said skirts, constantly pressing against said outer flange faces, and a knob secured on said pointer indexing means for affording manual positioning thereof along said channel means.

3. A decimal indexing channel unit adapted for mounting on a computing machine in decimalizing relation to a register of the machine, said indexing channel unit comprising channel means formed of a pair of substantially outwardly divergent longitudinal flanges projecting from web means therebetween and terminating in parallel longitudinal outer edges for defining a guide passageway; movable pointer indexing means comprising a slide-body having an outwardly visible top face and having support surfaces beveled to conform with the divergent inner surfaces of said flanges for sliding contact engagement therewith and for longitudinal guidance thereby, said slide-body being formed with support limit shoulders extending therefrom between said support surfaces and said top face for overlying and sliding on the edges of said flanges and with a groove transverse the said visible top face of said slide-body and its said shoulders, and C-spring means constructed and arranged for being inset said groove with the center portion of said spring means protruding upward of said slide-body, with the extremities resiliently embracing said flanges and with an intermediate portion between each extremity and said center portion of said spring means engaging said slide-body at said shoulders in said groove for spreading said extremities of said spring means upon depression of said protruding center portion for freeing said spring means extremities from embracing contact with said flanges thereby to facilitate endwise shifting of said indexing means, along said channel means, said C-spring means forming a dec-

imalizing index for locating the decimal point in a computation on said register

4. A decimal indexing channel unit adapted for mounting on a computing machine in decimalizing relation to a register of the machine, said indexing channel unit comprising channel means formed of a web having parallel longitudinal spaced edges, and a pair of substantially outwardly divergent longitudinal flanges projecting from said edges of said web therebetween, for defining a guide passageway, said flanges each having an inner and an outer surface; movable pointer indexing means comprising a slide body having an outwardly visible top face and support surfaces beveled to conform with the divergent inner surfaces of said flanges for sliding and supporting engagement with said flanges and for longitudinal guidance thereby, said slide-body being formed with a groove transverse the said visible top face of said slide-body, and C-spring means constructed and arranged for being inset said groove with the center portion of said spring means protruding upwardly from said top face of said slide-body, with the extremities of said spring resiliently embracing said outer surfaces of said flanges, and with a pair of intermediate spring portions, one said portion being between each extremity and said center portion of said spring, said intermediate spring portions engaging said slide-body in said groove for spreading said extremities upon depression of said protruding portion for freeing said spring extremities from embracing contact with said flanges, thereby to facilitate endwise shifting of said indexing means along said channel means, said C-spring means forming a decimalizing index for locating the decimal point in said register.

5. The combination according to claim 4 wherein said slide body is further characterized as having a bottom face interconnecting said support surfaces, and said bottom face being substantially wider laterally than said web, so that said support surfaces are spaced in relation to the spacing of the flanges of said channel means as to maintain said bottom face spaced from said web in said passageway, out of rubbing contact with said web.

6. A decimal indexing channel unit adapted for mounting on a computing machine in decimalizing relation to a register of the machine, and comprising a plane channel web having parallel spaced first and second side edges, first and second longitudinal channel flanges projecting directly from the respective said side edges of said web, said flanges being continuously and entirely plane, and being mutually angularly divergent from the web, and with their outer edges being mutually parallel and coplanar, and parallel to said web, so that said outer edges form a pair of rails, a pointer indexing marker constructed and arranged for riding on both said rails, and comprising a plane marker body formed so as to be supported upon both said rails and having first and second longitudinal edges overlying and extending only to the outer corners of said rails, at least one pointer integral with and extending beyond a said longitudinal edge of said marker body, and being coplanar with said body, first retaining lug means depending from said first longitudinal edge of said marker body, and extending inwardly to lie against the outer surface of and conform to the angularity of said first longitudinal flange, and second lug means depending from said second longitudinal edge of said marker body and comprising a pair of resilient lug fingers extending longitudinally from said second lug means in opposite directions and resiliently bearing against the outer surface of said second longitudinal flange, for drawing said first retaining lug means against said first longitudinal flange and causing said pointer indexing marker and its first and second lug means to resiliently grippingly engage said channel flanges for variable positioning along said flanges.

7. A decimal indexing channel unit adapted for mounting on a computing machine in decimalizing relation to a register of the machine, said indexing channel unit comprising channel means formed of a web having parallel

longitudinal spaced edges, and a pair of substantially outwardly divergent continuously plane longitudinal flanges projecting directly from said edges of said web therebetween, for defining a guide passageway, said flanges each having an inner and an outer plane surface and an edge surface displaced from said web; movable pointer indexing means constructed and arranged for riding on the edge surfaces of said flanges and comprising a slide body formed of sheet material having two marginal edges, two spaced extensions on a first said marginal edge formed downwardly to conform to and grip the outer plane surface of one of said flanges for alignment and guidance thereby, and a resilient extension on the second said marginal edge formed downwardly to conform to and yieldably grip the opposing outer plane surface of the second of said flanges for yieldably holding said indexing means in decimalizing position along said channel means.

8. A decimal indexing channel unit adapted for mounting on a computing machine in decimalizing relation to a register of the machine, said indexing channel unit comprising channel means formed of a web having parallel longitudinal spaced edges, and a pair of substantially outwardly divergent continuously plane longitudinal flanges projecting directly from said edges of said web therebetween, for defining a guide passageway, said flanges each having an inner and an outer plane surface and an outer edge displaced from said web; movable pointer indexing means constructed and arranged for riding on the edges of said flanges and comprising a slide body having two marginal edges, two spaced extensions on a first said marginal edge formed downwardly to conform to and grip the outer plane surface of one of said flanges for alignment and guidance thereby and a resilient extension formed on the second said marginal edge formed downwardly to conform to and yieldably grip the opposing outer plane surface of the second of said flanges for yieldably holding said indexing means in decimalizing position along said channel means.

9. The combination according to claim 8 wherein ordinarily spaced indicia are carried on said web situated in ordinal alignment with and for corresponding permanently to the orders of said register on the visible face of said web between said flanges, and so that said flanges have their upper edges above said web so as to protect said indicia from engaging contact with an obliteration by said indexing means.

10. The combination according to claim 8 wherein said web comprises a visible face between said flanges, and wherein indicia are carried on said web corresponding positionally to the orders of said register on said visible face between said flanges, and so that said flanges space said movable indexing means from and protect said indicia from rubbing contact of said indexing means.

11. A decimal indexing channel unit adapted for mounting on a computing machine in decimalizing relation to a register of the machine, said indexing channel unit comprising channel means formed of a web having parallel longitudinal spaced edges, and a pair of outwardly divergent continuously plane longitudinal flanges projecting directly from said edges of said web therebetween, for defining a guide passageway, said flanges each having an inner and an outer plane surface and an edge surface displaced from said web; and movable pointer indexing means constructed and arranged for riding on the edge surfaces of said flanges and comprising a slide body having two marginal edges, two spaced extensions located at the extremities on a first said marginal edge and formed downwardly to conform to and grip the outer plane surface of one of said flanges for alignment and guidance thereby, and an extension located generally centrally on the second said marginal edge and formed downwardly and comprising a pair of laterally extending resilient fingers formed to grip the outer plane surface of the second of said flanges for yieldably holding said indexing means in a decimalizing position along said channel means.
